UNITED STATES PATENT OFFICE.

JOHN L. LAMB, OF MIAMI, OKLAHOMA.

MOLD FOR HOLLOW TILES.

Application filed November 4, 1922. Serial No. 599,029.

To all whom it may concern:

Be it known that I, JOHN L. LAMB, a citizen of the United States, residing at Miami, in the county of Ottawa and State of Oklahoma, have invented a new and useful Mold 5 for Hollow Tiles, of which the following is a specification.

This invention relates to hollow tiles for drainage, sewers, and other purposes and to 10 molds for making them.

The object of the invention is to provide a tile of this character which may be constructed to fit openings of various sizes and shapes.

15 Another object is to provide a tile of this character combining simplicity and ease of construction with the greatest possible utility and which may be repaired with the least possible digging and joining of parts, 20 the use of which discloses with certainty to the party laying, when a complete job has been effected.

Another object is to provide a simple and 25 efficient form for constructing circular pillars or posts.

With the foregoing and other objects in view which will appear as the description proceeds, the invention resides in the combination and arrangement of parts and in the 30 details of construction hereinafter described and claimed, it being understood that changes in the precise embodiment of the invention herein disclosed may be made within the scope of what is claimed without departing 35 from the spirit of the invention.

In the accompanying drawings:—

Figure 1 represents a side elevation partly in section of a mold used in forming a cylindrical post.

40 Figure 2 is a top plan view thereof.

Figure 3 is a transverse section taken on the line 3—3 of Fig. 1.

Fig. 4 is a side elevation partly in section of a cylindrical pillar constructed in the 45 mold shown in the above described figures.

Fig. 5 is an end elevation thereof.

Fig. 6 is an end elevation of a slightly different form of mold.

Fig. 7 is a top plan view with parts broken out and in section of another form of 50 mold for constructing semi-cylindrical tiles.

Fig. 8 is a longitudinal section thereof taken on the line 8—8 of Fig. 7.

Fig. 9 is a transverse section taken on the 55 line 9—9 of Fig. 7.

Fig. 10 is a detail perspective view of a

tile constructed by means of the mold shown in Figs. 7 to 9, and

Fig. 11 is an end elevation showing two of the tiles arranged to form a hollow conduit 60 or block.

In Figs. 1, 2 and 3 a form 1 is shown for molding a hollow concrete pillar or post such as that shown in Figs. 4 and 5. This form 1 comprises an outer longitudinally split casing 2, the longitudinal edges of which overlap and are provided with interengaging tongues 3 as shown clearly in Fig. 3.

This casing 2 is held in operative position 70 by any suitable means in addition to the interengaging tongues preferably by retaining bands 4 and by a cap 5, the flange 6 of which fits over one end of the casing 2 as shown in Fig. 1, and thereby assists in preventing spreading of the casing. A smaller cap 8 is carried by the cap 5, being secured thereto by a bolt 7. This cap 8 has a flange 9 concentric with the flange 6 but considerably wider and is designed to fit in a collapsible 75 core 10 located in casing 2 and now to be described.

The core 10 is composed of a longitudinally split tube of resilient sheet metal with the longitudinal edges thereof overlapping, said core having a tendency to contract and is normally held in expanded position by the flange 9 or cap 8 inserted at one end and by a cylindrical member 11 inserted in the other end. When this core 10 is mounted in the 80 casing 2 it is spaced from the inner wall of said casing a distance corresponding to the thickness of the wall of the hollow pillar or post to be formed and is retained in this position by the cap 8 carried by cap 5 and by 85 spring clips or gripping fingers 12 which are carried by the casing 2 and secured thereto in any suitable manner. These spring fingers 12 are here shown having hooks 13 at their inner ends which are engaged with the uppermost band 4 which surround the casing 2. The body portions 14 of these centering fingers are arranged flat against the outer face of the casing 2 and are provided at their upper ends with hook-like 90 bends 15 which fit over the edge of the casing 2 and then folded again upon themselves as shown at 16 and extended inwardly and outwardly to engage the core 10 and hold it centered, any number of these fingers may 95 be employed, three being here shown.

The flange 9 of the end cap 8 and tubular

member 11 are preferably oiled on their outer faces to facilitate their insertion and removal so that after the pillar or post has been molded these members may be readily 5 removed from the core 10 and thus permit said core to contract to facilitate its removal.

In the use of this form, the parts being in the position shown in Fig. 1, the concrete or 10 cement is poured into the space between the outer casing 2 and the core 10 completely surrounding said core and filling said space. After the poured cement hardens sufficiently, the mold or form is removed by withdrawing 15 the cap 5 which carries with it the inner cap 8. The spring clamp or retaining bands 4 are then removed from the casing 2, which permits said casing to expand and be easily slipped off the molded article.

20 The tubular member 11 is then drawn out of the core 10 which will permit said core to collapse or contract and be easily removed leaving a cylindrical post or pillar 17 such as that shown in Fig. 4. The side walls of 25 this pillar 17 may be varied in thickness as desired by changing the relative sizes of the casing 2 and the core 10 as will be understood.

In the form shown in Fig. 6, the core 10 30 is exactly like that described above, the casing 2' being similar to the casing 2, except that it is made rectangular in cross section instead of circular.

In Figs. 7, 8 and 9 another mold 20 is 35 shown designed to produce the tiles 30, one of which is shown in detail in Fig. 10, and in Fig. 11, two of them are arranged in superposed position to provide a hollow block or conduit having a bore extending 40 therethrough which is cylindrical in form.

The form employed for making these tiles comprises two side boards 21 and 22 of a width corresponding to the thickness of the tile 30 to be produced. These boards 21 45 and 22 are connected at their opposed ends by rods 23 and 24 which are removably mounted in said boards. Arranged between the boards at longitudinally spaced intervals are a plurality of transversely arranged partitions 25 preferably constructed of galvanized iron or the like and are spaced apart a distance corresponding to the length of the tiles to be molded. These partitions 25 are held in operative position by any suitable 50 means, cotter pins 26 being here shown extended transversely through the boards 21 and 22 with their furcations straddling the partitions as is shown clearly in Fig. 7.

Any desired number of these partitions 25 55 may be provided, according to the sizes of the mold, five being here shown and which operate to separate the individual tiles formed in the mold. These partitions have their upper edges cut out as shown in Figs. 65 7 and 8, said cut portions being of any de-

sired configuration according to the shape of the inner faces of the tiles to be molded, said cut outs being here shown semi-circular.

The side boards 21 and 22 are provided near their opposite ends in their upper edges 70 with seats 27 here shown semi-circular in form and which are designed to support cores 28 here shown semi-circular in form with their flat faces arranged flush with the upper edges of the board. 75

A longitudinally disposed core 29 is designed to be supported in the cut out upper edges of the partitions 25, said core being similar in cross sectional contour to the cores 28 with its flat upper face arranged flush 80 with the upper faces of said cores and with the upper edges of the boards.

In the use of the mold 20, the parts being removable as shown in Fig. 7, the cement is 85 poured around the cores 28 and 29 between them and the side boards 21 and 22 and between the transverse partitions 25, and completely fills the spaces surrounding these parts as is shown clearly in Fig. 8. After the poured cement hardens, the cores 28 and 29 are lifted out and the boards 21 and 22 separated by removing the rods 23 and 24 and withdrawing the cotter pins 26. After 90 these boards have been removed, the tiles formed in the compartments between the 95 partitions 25 may be readily removed and may be used for any purpose desired.

When a conduit is to be formed, two of the tiles 30 are superposed with their hollow portions facing each other as shown in Fig. 100 11, thus forming a tile with a circular opening 31 extending therethrough. In laying tiles of this character for use in this way, the lower members are first placed in position and earth tamped around them up to 105 a point substantially flush with their upper faces. The cooperating tiles are then placed on the tiles so embedded as shown in Fig. 11 and are secured thereto by means of mortar arranged in the joints between the 110 superposed tiles, a swab being preferably used to prevent the mortar filling in the bore in the tiles. It is understood of course, that as the tiles are laid, the swab is moved longitudinally so as to clean out any mortar 115 which may drop into the interior of the tile.

From the above description it will be readily seen that the blocks or tiles constructed as herein shown and described are 120 comparatively light and may be easily laid at any level although the weight thereof may be varied in construction by increasing or diminishing the thickness of the walls.

While these tiles are primarily intended to 125 be used as drain tiles, obviously concrete forms may be so constructed as to produce a building block by merely extending or lengthening the edges thereof and the opening inside forms an air chamber in each layer of blocks.

Various changes in the form, shape, proportion and other minor details of construction may be made without departing from the principle or sacrificing any of the advantages of the claimed invention.

5 I claim:—

1. In a mold of the class described, longitudinally split resilient metal inner and outer casings of different diameters, the edges of the slit of each casing being arranged in lapping relation, whereby the inner casing is normally contractable and the outer casing normally expansible, a cap having a flange to fit around the outer casing 10 at one end thereof, a similar cap mounted on and secured to the inner face of said first mentioned cap and adapted to fit in said inner casing forming a reinforcement and spreader therefor, a tubular member for insertion in the other end of said casing, and retaining bands arranged around the outer casing.
- 15 2. In a mold of the class described, longitudinally split resilient metal inner and outer casings of different sizes, the edges of the split being arranged in lapping relation whereby the inner casing is normally con-

tractable and the outer casing normally expansible, a cap having a flange to fit around the outer casing at one end thereof, a tubular member carried by the inner face of said cap to fit within the inner casing to hold it against collapse, retaining bands arranged around the outer casing, a tubular member for insertion in the other end of said inner casing, and centering fingers carried by the open end of the outer casing to engage the adjacent end of the inner casing to hold said end centered relatively to the outer casing, said fingers having hooks, at their inner ends, the body portions of the fingers being arranged flat against the outer face of the casing and provided at their upper ends with hook-like bends to fit over the edge of the casing and then folded again upon themselves and extended inwardly and outwardly to engage the core and hold it centered.

30 35 40 45 In testimony that I claim the foregoing as my own, I have hereto affixed my signature in the presence of two witnesses.

JOHN L. LAMB.
